UNITED STATES PATENT OFFICE.

CASSIUS M. WALKER, OF PUEBLO, COLORADO, ASSIGNOR TO THE MILLER ELECTRIC SWITCH COMPANY, A CORPORATION OF COLORADO.

CONTROLLING-CAM.

1,075,799.

Specification of Letters Patent. Patented Oct. 14, 1913.

Application filed February 26, 1912. Serial No. 679,917.

To all whom it may concern:

Be it known that I, CASSIUS M. WALKER, a citizen of the United States, residing at Pueblo, Colorado, have invented certain new and useful Improvements in Controlling-Cams, of which the following is a specification.

My invention relates to improvements in a controlling cam adapted to use in electro-mechanical switches of construction where a free pivotal arm is required to be centered.

The objects of my improvement are to provide a means to dispense with the use of a centering spring or springs, and to furnish a device to center the arm actuating means, and at the same time this furnishes a support for a centering arm. I attain these objects by the mechanism illustrated in the accompanying drawings, in

20 which,—

Figure 1 is a top plan view of an electro-mechanical switch in which my device is arranged; Fig. 2 is a cross sectional view of a containing box showing the mechanism in 25 elevation; and Fig. 3 is a perspective view of the underneath side of the device showing my invention.

It is not my purpose to ask for any broad invention in electromechanical switches, but 30 in certain types of mechanical switches, patents for which have been issued, there is provided a containing box 1 with solenoid 2, a plunger 3, spring means 4 to return the plunger, with pivotal throwing arm 5 attached pivotally to the plunger at 6. The 35 other end of the throwing arm 5 has a boss 13 adapted to engage the cam piece 7 to

which is connected through the shaft 8 the connecting means to a switch tongue.

I provide a controlling cam 9, V shaped, 40 to be attached to a division wall or support 11 by bolt means 10. This controlling cam piece extends out under the throwing arm 5. A boss 12 is attached to the underside of the throwing arm 5 and adapted to engage the 45 inner sides of the cam piece 9. When the plunger 3 is released by the current being turned off from the solenoid 2, the spring means 4 returns the plunger, and the boss 12 on the throwing arm 5 travels on the inside of the cam piece 9 to near the pointed end thereof and thus the throwing arm 5 is supported upon said controlling cam piece 9 and guided to the center position which said throwing arm is to occupy when not 55 being actuated.

I claim.

In an electromechanical switch device wherein is provided a solenoid; a plunger therein, with spring means for return; a 60 throwing arm pivotally attached to said plunger; a cam piece connected by intermediate means with a switch tongue; to which is applied a controlling cam, V shaped, attached to supporting walls and 65 disposed beneath the said throwing arm, and a boss on the underneath side of said throwing arm adapted to operate on the interior side of said V shaped controlling cam piece; all as described.

CASSIUS M. WALKER.
